UNITED STATES PATENT OFFICE.

ROBERT C. STEVENS, OF ERIE, PENNSYLVANIA, ASSIGNOR TO SKINNER ENGINE COMPANY, OF ERIE, PENNSYLVANIA, A CORPORATION OF PENNSYLVANIA.

ENGINE VALVE-GEAR.

1,125,204.

Specification of Letters Patent. Patented Jan. 19, 1915.

Application filed January 25, 1913. Serial No. 744,202.

To all whom it may concern:

Be it known that I, ROBERT C. STEVENS, a citizen of the United States, residing at Erie, in the county of Erie and State of Pennsylvania, have invented certain new and useful Improvements in Engine Valve-Gear; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to valve-gear for operating engine-valves, and has for its object the provision of electro-magnetic mechanism adapted to operate engine-valves to permit the passage of steam therethrough, 20 to or from the piston-cylinder of an engine.

The features of my invention are herein-after pointed out and explained and are illustrated in the accompanying drawings in which:

25 Figure 1, is a vertical, transverse section of an engine cylinder through one of the inlet valves thereof, showing my invention placed thereon. Fig. 2, is a diagrammatic view of my invention. Fig. 3, is a view of 30 the commutator mechanism of my invention, flattened out.

In these drawings, A, indicates an engine cylinder, B, an engine-valve, B', the valve-stem, b, the spring for maintaining the valve 35 B, normally in a closed position; C, indicates the engine-shaft.

Upon the valve-stem B', I secure a yoke D, of brass or other non-magnetic metal. This yoke D, is preferably provided with a 40 hollow cylinder d, which fits over the valve stem-support, d', and is provided with a small air vent hole d², so as to act as a dash-pot to prevent noise and injury to the valve B, by a too forcible closing of the valve B, 45 upon its seats. Upon the housing E, of the valve-stem B', I secure a support E', of brass or other non-magnetic metal and upon the upper end of this support E', I secure an electro-magnetic device F, preferably of 50 the solenoid type having its core F', secured to the yoke D, on the valve-stem B'. Upon the shaft C, of the engine I place a commutator G, (see Fig. 3) having an element g, of copper or other metal of desired adaptability for an electric conductor, the sur-

face of said element g, being suitably interspersed with non-conducting material g', of fiber or material of like nature. At the intermediate portion of the surface of this commutator G, the electric conducting element g, is continuous around the entire circumference of the commutator, while from desired points around said circumference it tapers toward the margins of the commutator as indicated by the reference letter g². 60 The continuous portion of the conductor element g, is indicated by the reference letter g³. Upon an arm H, secured to the engine frame, I slidably mount brush holders H', which support brushes h, in contact with the 70 commutator G, on the engine shaft C. I also place upon the arm H, in a permanent position thereon, a brush holder H², adapted to hold a brush h', in contact with the continuous portion g³, of the electric conducting element g, of the commutator G. It will of course be understood, that the brushes h, h, and h', are electrically insulated in their respective brush holders.

75 Mounted upon the engine frame I secure 80 a governor mechanism J, which is driven by means of a suitable power transmission device J', from the shaft C, of the engine, and is adapted to operate a bell-crank lever K. This bell-crank lever K, is operatively 85 connected to the slidable brush holders H', by means of the links K', and K².

From the electro-magnetic device F', above the valve at each end of the cylinder, electric conductors L, extend to the brushes h, and an electric conductor L', extends from the brush h, to one pole of an electric generator M; from the other pole of the generator M, an electric conductor N, extends to the opposite end of the coil in each of the electro-magnetic devices, connected with each of the engine valves. When the commutator G, is in the position shown in Fig. 1, of the drawings, the course of the electric current will be from the generator M, through the conductor L', to the brush h', and from thence through the element g, on the commutator G, to the brush h, and thence by one of the conductors L, to the upper end of the coil in the electro-magnetic device F, and thence back by one of the conductors N, to the generator. 95 100 105

It will be obvious from the fore-going description, that the rotation of the engine-shaft C, and the commutator G, thereon 110

will cause the brushes h' , to be in contact, alternately, with the elements g , on the commutator, thereby alternately breaking the circuit communicating with each of the electro-magnetic devices F , at each end of the engine cylinder, thereby causing each of said engine-valves B , to be alternately opened. It will likewise be obvious that as the speed of the governor mechanism J , increases, the brush holders H' , will be moved longitudinally on the arm H , so that the brushes h , will not be in contact so long a time, with the element g , on the commutator G , thereby permitting the valve B , to close in a shorter interval after it has opened.

Having thus fully described my invention so as to enable others to construct and use the same, what I claim as new and desire to secure by Letters-Patent is:-

- 20 1. The combination in an engine valve gear, of an engine cylinder, a valve communicating therewith, a valve-stem secured to said valve, a solenoid coil, a core thereon secured to said valve-stem, an engine shaft, a circuit interrupter adapted to rotate in unison with said shaft, brushes in spaced relation to each other adapted to contact with said interrupter, an electric generator, an electric conductor leading from one pole of said generator to one pole of said solenoid, an electric conductor leading from the opposite pole of said generator to one of said brushes, and another electric conductor leading from the other of said brushes to the opposite pole of said solenoid, substantially as and for the purpose set forth.
- 25 2. The combination in an engine valve gear, of a valve, a valve-stem, a yoke of non-magnetic material secured to said valve-stem, a spring to retain said valve in a normally closed position, a solenoid coil supported above said yoke, a solenoid core within said coil and secured to said yoke, an engine shaft, a circuit interrupter adapted to rotate in unison with said shaft, brushes in spaced relation to each other contacting with said interrupter, a generator, a conductor leading from said generator to one pole of said solenoid, and another conductor leading from the opposite pole of said generator to one of said brushes, and from the other brush to the opposite pole of said solenoid, substantially as and for the purpose set forth.
- 30 3. The combination in an engine valve gear, of a valve, a valve-stem secured thereto, a yoke of non-magnetic material secured on said valve-stem, a spring adapted to retain said valve in a normally closed position, a solenoid coil above said yoke, a solenoid core within said coil and secured on said yoke, an engine shaft, a circuit interrupter adapted to rotate in unison with said shaft, a stationary brush contacting with said interrupter, another brush laterally

movable with relation to said stationary brush and contacting with said interrupter, a governor mechanism, lever mechanism adapted to be actuated by said governor mechanism to move said movable brush, a generator, a conductor leading from one pole thereof to one pole of said solenoid, and another conductor leading from the opposite pole of said generator to one of said brushes, and from the other of said brushes to the opposite pole of said solenoid, substantially as and for the purpose set forth.

4. The combination in an engine valve-gear of a valve, a valve-stem secured to said valve, a dash-pot mechanism adapted to be operated by said valve-stem, an electro-magnetic device adapted to raise said valve off of its seat, valve-stem and dash-pot mechanism in one direction, a spring to operate the same in the opposite direction, an engine-shaft, a commutator adapted to rotate in proper time with said shaft, brushes operating on said commutator, an electric generator, an electric conductor, from one pole of said generator to one pole of said electro-magnetic device, and an electric conductor leading from the opposite pole of said generator to one of said brushes, and from one of the other of said brushes to the opposite pole of said electro-magnetic device, substantially as and for the purpose set forth.

5. The combination in an engine valve-gear, of a valve, a valve-stem secured to said valve, a support for said valve-stem, a hollow cylinder having a closed end and provided with a vent opening, secured on said valve-stem and fitting over said valve-stem support, an out-turned annular flange on said cylinder, a valve-housing inclosing said cylinder, a spring on said cylinder between said out-turned annular flange and said valve-housing adapted to maintain said valve in a normally closed position, an electro-magnetic device adapted to operate to open said valve, an engine shaft, a commutator adapted to rotate in unison with said shaft, brushes operating on said commutator, an electric generator, an electric conductor leading from one pole of said generator to one pole of said electro-magnetic device, and an electric conductor leading from the opposite pole of said generator to one of said brushes and from one of the other of said brushes to the opposite pole of said electro-magnetic device, substantially as and for the purpose set forth.

6. The combination in an engine valve-gear of a valve, a valve-stem secured to said valve, dash-pot mechanism adapted to be operated by said valve-stem, an electro-magnetic device adapted to raise said valve off of its seat, valve-stem and dash-pot mechanism in one direction, a spring to op-

erate the same in the opposite direction, a circuit connected to said electro-magnetic device controlling said valve, and a circuit interrupter operated by some moving part 5 of the engine and controlling said circuit.

7. The combination in an engine valve gear, of a valve, a valve-stem secured to said valve, a support for said valve-stem, a hollow cylinder having a closed end and provided with a vent opening, secured on said valve-stem and fitting over said valve-stem support, an out-turned annular flange on 10 said cylinder, a valve-housing inclosing said cylinder, a spring on said cylinder, between 15 said out-turned annular flange and said

valve-housing adapted to maintain said valve in a normally closed position, an electro-magnetic device adapted to operate to open said valve, a circuit connected to said electro-magnetic device, controlling said 20 valve, a circuit connected to said electro-magnetic device, and a circuit interrupter operated by some moving part of the engine and controlling said circuit.

In testimony whereof I affix my signature, in presence of two witnesses:

ROBERT C. STEVENS.
